UNITED STATES PATENT OFFICE.

FERDINAND J. WENDELL, OF NEW YORK, N. Y.

PRINTING-PLATE AND BASE.

SPECIFICATION forming part of Letters Patent No. 659,385, dated October 9, 1900.

Application filed March 27, 1900. Serial No. 10,323. (No model.)

To all whom it may concern.

Be it known that I, FERDINAND J. WENDELL, a citizen of the United States, and a resident of New York city, in the State of New York, have invented Improvements in Printing-Plates and Bases, of which the following is a specification.

This invention relates to printing-plates and more particularly to stereotype-plates, and has for its object to lighten as much as possible plates having deep side bearing-surfaces adapted to keep the plate from being drawn upward by suction when the printing-roller is passed over it, while still maintaining the plate sufficiently strong to withstand the pressure in the chase.

Heretofore it has been necessary to make deep plates that are not locked to a base comparatively heavy in order to withstand the lateral pressure of the locking-up devices, such as the column-rules, chase, &c. When an unbending flat surface, such as the side of a column-rule, is brought to bear forcibly against another flat surface, if the extremities of this other surface withstand the pressure then the portion between such extremities may be fragile without danger of bending or breaking from lateral pressure. I make use of this principle to provide a very light but strong plate.

In the accompanying drawings, Figure 1 represents an end view of a printing-plate and base made according to my invention and showing column-rules bearing against the sides thereof. Fig. 2 is a similar view of a slight modification.

Referring to Fig. 1, the plate A is provided with thin vertical flanges a, raising the plate nearly type-high, the said flanges being sufficiently deep to prevent the plate from being drawn upward by suction of the printing-roller. These flanges a rest upon a base B, just deep enough to further raise the plate A type-high. This base B forms a strong lateral brace at the lower edge of each side of the combined plate and base, against which a column-rule or other furniture bears and prevents the flanges from being bent inward from lateral pressure. The plate A itself forms a strong lateral brace at the upper edge of each side, so that the portion between these braced edges—that is, the flanges a—

are not subjected to much lateral pressure and may be made quite thin.

So far as already described the plate A' of Fig. 2 and its side flanges a' are the same as the plate A and flanges a. To assist the flanges a or a' in preventing the weight of the impression devices bending the plate A or A' downward, one or more vertical braces or legs bearing between the plate and base may be provided. Fig. 1 shows such a vertical brace or leg a⁵ formed with the plate A and resting on the base B, while Fig. 2 shows two vertical braces or legs b b formed with the base B' and on which the plate A' rests. It is evident that any number of such vertical braces may be formed either with the plate or the base to suit the width of the plates. The plate shown in the drawings is about the width of a column of newspaper matter; but it may be of any width, even to a whole page.

I claim as my invention—

1. The combination of a printing-plate provided with thin vertical flanges raising the plate nearly type-high and forming deep side bearing-surfaces with little extra weight, with a base further raising the plate just type-high, and forming a brace at the bottom of the combined plate and base to prevent the said flanges being bent inward by lateral pressure when the parts are locked up, substantially as described.

2. The combination of a printing-plate provided with thin vertical flanges raising the plate nearly type-high and forming deep side bearing-surfaces with little extra weight, with a base further raising the plate just type-high and forming a brace at the bottom of the combined plate and base to prevent the said flanges being bent inward by lateral pressure when the parts are locked up, and one or more longitudinal braces or legs between the plate and base intermediate of the said flanges.

In testimony whereof I have signed my name to this specification in the presence of two subscribing witnesses.

FERDINAND J. WENDELL.
